UNITED STATES PATENT OFFICE

CHARLES F. HENNEY, OF DAYTON, OHIO, ASSIGNOR TO FRIGIDAIRE CORPORATION, OF DAYTON, OHIO, A CORPORATION OF DELAWARE

REFRIGERATING APPARATUS

Application filed April 30, 1930. Serial No. 448,583.

The present invention relates to evaporators for refrigerating apparatus and more particularly to evaporators of the flooded type.

5 One of the objects of the present invention is to generally improve relatively long horizontal evaporators of the flooded type.

Another object is to improve flooded type evaporators in which the ducts are relatively 10 flat. In carrying out this object it is a more specific object to provide an enlarged portion in the upper part of the flat duct to provide an enlarged surface of the liquid.

Further objects and advantages of the present invention will be apparent from the following description, reference being had to the accompanying drawings, wherein a preferred form of the present invention is clearly shown.

20 In the drawings:

Fig. 1 is a front view of a refrigerator, the upper part being in section showing one form of my improved evaporator.

Fig. 2 is a fragmentary view partly in section taken on line 2—2 of Fig. 1;

Fig. 3 is a view of the header of the evaporator shown partly in section, the section being taken on line 3—3 of Fig. 1;

Fig. 4 is a top plan view of the evaporator; 30 Fig. 5 is a sectional view taken on line 5—5 of Fig. 4;

Fig. 6 is an end view of a display type refrigerator cabinet partly in section showing a modified form of evaporator;

Fig. 7 is a rear view of the display case partly in section, the section being taken on line 7—7 of Fig. 6;

Fig. 8 is a top plan view of the evaporator shown in Fig. 6;

40 Fig. 9 is a side view of such evaporator, and Fig. 10 is a sectional view taken on line 10—10 of Fig. 9.

For the purpose of illustrating one form 45 of my invention, I have shown an evaporator in combination with a cabinet in which the

cooling chamber is located in the upper part thereof. This cabinet shown at 20 is provided with a chilling chamber or compartment 21 having a door opening 22 through which the evaporator 24 can be removed. 50 This door opening is closed by a door 25. The cabinet 20 also includes a food compartment or compartments 26 closed by doors 27. A baffle 28 is disposed between these two compartments for directing air and for catching condensate dripping from the evaporator. 55

In the specific illustration the evaporator is shown as of the flooded type in which the flow of refrigerant thereto is controlled by the quantity of refrigerant in the evaporator. 60 It comprises a header 30 forming a reservoir for liquid refrigerant. Liquid refrigerant is delivered to the header from compressing mechanism through a coupling 31 and is withdrawn from the header through a coupling 32. These couplings are carried by a removable head 33. The flow of refrigerant through header 30 is controlled by a float 35 which actuates a needle valve 36 for cutting off the flow through the coupling 31 when a predetermined level of liquid refrigerant is attained within the header. The outlet of the evaporator is in the form of a tube 37 which connects with the coupling 32 and is provided with an oil overflow opening 38 for the purpose of draining the oil from the evaporator in case there is an excess quantity of oil therein. 70 75

In order to cool spaces substantially removed horizontally from the header, I provide a series of ducts 40 connected to one cylindrical side of the header and a similar series of ducts 41 connected to the opposite side of the header. These ducts are preferably formed of round tubing, the lower parts of which are squashed to provide tall narrow portions 43 and enlarged or flared portions 44. In the specific illustration a 2 inch outside diameter tube is used. The ends of the ducts 40 and 41 remote from the header are her- 80 85 90

metically sealed, while the opposite ends are hermetically joined with the header. In order to increase the heat transfer surface of the tubes I provide a plurality of fins 46 having key-hole shaped slots therein to conform to the keyhole contour of the ducts. In the preferred embodiment one fin is connected to a plurality of ducts. In addition to providing the increased heat transfer surface of the ducts, the fins 46 closely embrace the ducts so as to prevent bulging of the lower portions 43 thereof in case of excessive pressure within the evaporator.

The evaporator shown in Figs. 8 and 9 is particularly adaptable to refrigerators in which the cooling compartment is relatively long horizontally and relatively narrow longitudinally. One of these types of refrigerators is shown in Figs. 6 and 7 in the form of a display case 50. The upper insulated portion of the display case 50 forms a food storage compartment 51 and a chilling chamber or compartment 52 separated by a baffle 53. The lower portion of this display case forms a compartment 55 in which other parts of the refrigerating apparatus may be placed or which may be used as a storage chamber. In the specific illustration two evaporators 56 are placed within the chilling compartment 52. These evaporators are carried by bracket 57 for spacing same from the floor of the compartment so as to provide a space below the evaporator for the flow of air. The upper part of the evaporator is spaced from the top of the compartment for the entrance of air which flows downwardly over the evaporator. A removable cover 59 is provided for compartment 52 so as to provide access to and for the removal of the evaporator.

In this modification only two ducts 40 are shown, these ducts are connected with the end 60 of the header 30. Each fin 46 is connected with both of the ducts.

In refrigerating systems in which a quantity of oil is retained for revolving parts, for example, parts of the compressor, some of the oil is delivered with the refrigerant into the evaporator and in the type of system in which the refrigerant used is heavier than the lubricant, the oil will form a blanket within the evaporator. In the specific illustration, SO_2 is used as a refrigerant and the oil is known as Suniso No. 1, manufactured by the Sun Oil Company, having a specific gravity varying between .900-.918 at 60° Fahrenheit. The float 35 maintains the refrigerant level substantially at 61, while the lubricating level is indicated at 62. The ducts 40 of Figs. 8 and 9 and the ducts 40 and 41 of the evaporator 24 have their lower portions 43 connected with the header 30 below the surface of liquid refrigerant while the upper portions 44 communicate with the free space above the lubricant level in the header. Thus a free space 64 is provided throughout the length

of ducts 40 and 41. By providing a free space directly above all of the refrigerant in the ducts, the lubricant can readily separate from the refrigerant and therefor no oil pockets will be formed in portions of the evaporator, which pockets would prevent the proper operation thereof. Also by this arrangement gas bubbles may flow in their natural manner, namely upwardly, and due to constant ebullition, a quantity of oil is carried with the gas bubbles into the free space whence it is delivered through the outlet 37 with the refrigerant to the compressor. By constantly withdrawing a quantity of oil with the gas only a small layer of oil will collect upon the refrigerant.

One of the improvements in the present invention is the enlargement of the upper parts of the ducts 40 and 41 as at 44. If the ducts are maintained the same width at the upper end as at the lower end 43, capillary oil plugs would be present above the liquid refrigerant. Then an excessive pressure would be necessary below the oil for breaking same. In accordance with the present invention, I enlarged the upper portion of the ducts 40 and 41 beyond the capillary limit or bridge of the oil. In the specific example the lower portion has an inside diameter of three eighths of an inch while the upper enlarged portion has an inside diameter of three quarters of an inch. By this arrangement I find that gas bubbles will pass more readily through the blanket of oil and in this manner the efficiency of the evaporator is increased because of the decrease in differential between the back pressure and the pressure of the refrigerant below the blanket of oil.

Due to the fact that the refrigerant can pass through the oil more readily, vaporization within the evaporator is more constant, that is, there is a continuous bubbling through the oil and no explosions, due to super-heating of the refrigerant, will occur. In this manner a constant quantity of oil will be carried from the evaporator with the gas and therefore the blanket of oil is maintained at a minimum. The enlarged portion 44 also provides a relatively large disengaging area for liquid refrigerant. The velocity within the portion 44 is decreased because of the enlargement so that if any liquid refrigerant is forced through the oil with the gas, the velocity is such that the liquid will not be drawn into the header as liquid but is permitted to vaporize or fall back into the main body of liquid in the ducts.

In addition to the above the upper cylindrical flared portion 44 increases the strength of the top of the ducts in order to aid the fins in preventing bulging of the same.

While the form of embodiment of the invention as herein disclosed, constitutes a preferred form, it is to be understood that other

forms might be adopted, all coming within the scope of the claims which follow.

What is claimed is as follows:

1. An evaporator for a mechanical refrigerator comprising, a reservoir, a tall narrow keyhole shape in cross section duct extending horizontally from the reservoir, said reservoir and duct being adapted to contain a quantity of liquid refrigerant and a blanket 10 of oil floating on the refrigerant, means for maintaining a substantially constant level of liquid refrigerant in said reservoir, the duct having its lower portion connected below the surface of liquid refrigerant and its upper 15 portion with the free space above the oil in the reservoir, said duct being flared outwardly at the oil blanket.

2. An evaporator for a mechanical refrigerator comprising, a cylindrical reservoir, a tall narrow keyhole shape in cross section duct connected with a cylindrical side wall of the reservoir and extending horizontally from said reservoir, said reservoir and duct being adapted to contain a quantity of liquid 25 refrigerant and a blanket of oil floating on the refrigerant, means for maintaining a substantially constant level of liquid refrigerant in said reservoir, the duct having its lower portion connected below the surface of liquid refrigerant and its upper portion with the free space above the oil in the reservoir, said duct being flared outwardly at the oil blanket.

3. An evaporator for a mechanical refrigerator comprising, a cylindrical reservoir, a plurality of tall narrow keyhole shape in cross section ducts connected with a cylindrical side wall of the reservoir and extending horizontally from said reservoir, said reservoir and ducts being adapted to contain a quantity of liquid refrigerant and a blanket of oil floating on the refrigerant, means for maintaining a substantially constant level of liquid refrigerant in said reservoir, the ducts having their lower portions connected below the surface of liquid refrigerant and their upper portions with the free space above the oil in the reservoir, said ducts being flared outwardly at the oil blanket.

4. An evaporator for a mechanical refrigerator comprising, a cylindrical reservoir, a plurality of tall narrow keyhole shape in cross section ducts connected with a cylindrical side wall of the reservoir and extending horizontally from said reservoir, said reservoir and ducts being adapted to contain a quantity of liquid refrigerant and a blanket of oil floating on the refrigerant, means for maintaining a substantially constant level of liquid refrigerant in said reservoir, the ducts having their lower portions connected below the surface of liquid refrigerant and their upper portions with the free space above the oil in the reservoir, said ducts being flared

outwardly at the oil blanket, and fin means thermally connected with said ducts.

5. An evaporator for a mechanical refrigerator comprising, a cylindrical reservoir, a plurality of tall narrow keyhole shape in cross section ducts connected with a cylindrical side wall of the reservoir and extending horizontally from said reservoir, said reservoir and duct being adapted to contain a quantity of liquid refrigerant and a blanket 75 of oil floating on the refrigerant, means for maintaining a substantially constant level of liquid refrigerant in said reservoir the duct having its lower portion connected below the liquid refrigerant level and its upper portion with the free space above the oil level in the reservoir, said duct being flared outwardly at the oil blanket, and a plurality of fin means arranged transversely of the ducts and bridging the space between same.

6. An evaporator for a mechanical refrigerator comprising, a reservoir for liquid refrigerant, means for maintaining a substantially constant level of liquid refrigerant in said reservoir a plurality of tall narrow keyhole shape in cross section ducts extending horizontally from the reservoir, one of said ducts being connected to one side of the reservoir and another of said ducts to a different side of said reservoir, said ducts having a lower portion of an end of each connected below the surface of liquid refrigerant and the upper portions of said ends connected with the free space above the liquid.

7. An evaporator for a mechanical refrigerator comprising, a reservoir for liquid refrigerant, means for maintaining a substantially constant level of liquid refrigerant in said reservoir, a plurality of tall narrow keyhole shape in cross section ducts extending horizontally from the reservoir, one of said ducts being connected to one side of the reservoir and another of said ducts to the opposite side of said reservoir, said ducts having a lower portion of an end of each connected below the surface of liquid refrigerant and the upper portions of said ends connected with the free space above the liquid.

8. An evaporator for a mechanical refrigerator comprising, a horizontally elongated and cylindrical reservoir for liquid refrigerant, means for maintaining a substantially constant level of liquid refrigerant in said reservoir, a plurality of tall narrow keyhole shape in cross section ducts extending horizontally from one side of the reservoir, similar ducts extending from the opposite side of said reservoir, said ducts having a lower portion of an end of each connected below the surface of liquid refrigerant and the upper portions of said ends connected with the free space above the liquid.

9. An evaporator for a mechanical refrigerator comprising a reservoir, a tall, narrow

duct extending horizontally from the reservoir, said reservoir and duct being adapted to contain a quantity of liquid refrigerant and a blanket of oil floating on the refrigerant, means for regulating the level of liquid refrigerant within the reservoir, the cross section of said duct having the shape of a key-hole, the narrow lower portion of the duct being connected below the surface of the liquid refrigerant and the rounded upper portion being above the surface of liquid refrigerant.

In testimony whereof I hereto affix my signature.
